UNITED STATES PATENT OFFICE.

ROBERT KUCERA, OF BUCHANAN, VIRGINIA.

MEANS FOR FEEDING SHEET-METAL BLANKS.

1,186,665.

Specification of Letters Patent. Patented June 13, 1916.

Application filed November 11, 1915. Serial No. 60,935.

To all whom it may concern:

Be it known that I, ROBERT KUCERA, a citizen of the United States, resident of Buchanan, in the county of Botetourt and State of Virginia, have made a certain new and useful Invention in Means for Feeding Sheet-Metal Blanks; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a side view of the invention as applied. Fig. 2 is a plan view of the invention. Fig. 3 is a section on the line 3—3, Fig. 2.

The invention has relation to machines 20 for feeding blanks in the manufacture of cans or containers of sheet metal or tin plate, and particularly to means for feeding the circular blanks or disks for the ends of caps of said cans to the die or press.

25 The invention consists in the novel construction and combinations of parts as hereinafter set forth.

In the accompanying drawings illustrating the invention, the numeral 2 designates 30 the press, having the lower die 3, and the upper reciprocatory die 4, the disks being commonly fed to said lower die by hand, which is a slow process.

My invention consists of a table or platform 5, mounted in front of the die press, where the operator has been accustomed to sit, a suitable holder for the circular blanks being located upon said platform and consisting preferably of a block 6, having a part 40 cylindrical recess 7, and four standards 8, 8, two of which are mounted upon said block, and are shorter than the other or rear standards, which are mounted directly upon the table.

45 A horizontal reciprocatory arm or finger 9 works in suitable guides 10 of said table, and is provided forwardly with an indented end 11 for engagement with the lowermost blank of the pile and in rear with suitable 50 operating mechanism 12, including usually a spring 12¹ to return the reciprocatory arm to normal position after each forward stroke thereof.

In order that but one blank at a time shall 55 be fed at each stroke of the arm or finger, an adjustable gage 13 is mounted upon the

block 6, centrally of the recess of said block, said gage having a forwardly extending screw 14, the head 14' of which bears against the forward face of the block, to hold the 60 gage truly to its vertical position, said screw working in a slot 15 of the block, and the upper end of the gage being turned forwardly horizontally over the top of the block at 16, a vertical screw 16', working in 65 a threaded seat 17 of the block, and having a collar 18 located below the end 16 of the gage and between the same and the block. The vertical screw is provided with a head 18', which is turned by hand to adjust the 70 gage.

The lower beveled end of the gage is separated from the table by a space 19 just sufficient to allow one blank to pass, the block 6 having an opening of the full diameter or 75 breadth of the blank and of greater thickness than the individual blanks, to allow blank of different thicknesses to pass upon adjustment of the gage.

The blanks are usually somewhat irregular and commonly slightly dished, so that ordinarily if the convex side of the lowermost blank is located below, the marginal upper edge of the blank would be raised above the lower edge of the gage, and the 80 arm or finger in its forward movement would pass under the blank and raise the 85 pile of blanks without feeding any of them. Or, in case the rear edge of the blank is sufficiently low, the arm or finger will strike 90 the blank, but the forward edge of the blank being raised, the blank will not pass below the gage, resulting in bending of the blank and possible jamming in and breakage of the machine, time and trouble being needed 95 to correct matters. And in case the lowermost blank has its convex side on top, the forward edge of the blank will at the start of the feeding at once pass under the gage and the feeding will be properly accomplished. 100

In order therefore to receive the lower convexity or depression of the lowermost dished blank and lower the level of the blank so that its raised marginal edge shall 105 be brought below the lower edge of the gage, the table is provided with a recess 22 in the floor of the holder for the pile of blanks, said recess being of a diameter slightly less than that of the individual blanks, the marginal portion of the lowermost blank resting upon the table. And in order that the 110

blank in being fed forward shall not rise above the lower edge of the gage and become bent, without effective feeding, this gage is set immediately adjacent to the pile of blanks, and the blank at the start of its movement forward, by the reciprocatory arm or finger, at once passes under the gage and is fed out at the opposite side thereof.

- 10 In order that the blanks in being fed under the gage and block shall not be jammed against each other, feed rollers 20, 20 are provided immediately adjacent to the forward face of the block, said rollers being run by suitable gearing 21 at a rate of speed 15 higher than that of the feed of the blanks, so that the blanks will be gripped by the rollers and pulled from under the gage and block faster than they are fed by the reciprocatory arm.
- 20 The gearing 21 consists usually of sprocket gearing 21', connecting the shaft of the upper of the feed rollers with the driving shaft 21² of the press, and intermeshing gears upon said rollers.
- 25 The invention is equally applicable to the feeding of rectangular blanks, the recess below the pile of blanks serving to receive any convexities or irregular depressions thereof that would otherwise interfere with the 30 proper feeding, as stated.

I claim:—

1. In feeding means for sheet metal blanks, a table, a reciprocatory push rod working in guides of said table, a holder for 35 a pile of blanks mounted upon said table, said table having a recess in the floor of said holder of dimensions less than that of the individual blanks, and a gage immediately adjacent to said recess.
- 40 2. In feeding means for sheet metal blanks, a table, a reciprocatory push rod working in guides of said table, a holder for a pile of blanks mounted upon said table, said table having a recess in the floor of said

holder of dimensions less than that of the 45 individual blanks, a gage immediately adjacent to said recess, feed rollers adjacent to said gage, and means for rotating said rollers at a speed greater than that of said push rod.

50 3. In feeding means for sheet metal blanks, a table, a reciprocatory push rod working in guides of said table, a holder for a pile of blanks consisting of a block upon said table having a recess, short standards 55 mounted upon said block and rear standards upon the table, said table having a recess in the floor of said holder of dimensions less than that of the individual blanks, and a gage mounted upon said block centrally of said recess of the block, and immediately adjacent to the recess in the floor of the holder.

60 4. In feeding means for sheet metal blanks, a table, a reciprocatory push rod working in guides of said table, a holder for a pile of blanks consisting of a block upon said table having a recess, short standards 65 mounted upon said block and rear standards upon said table, said table having a recess in the 70 floor of said holder of dimensions less than that of the individual blanks, a gage mounted upon said block centrally of the recess of the block and immediately adjacent to the recess in the floor of the holder, said 75 block having a horizontal opening of breadth equal to that of the blanks and of a height greater than the thickness of the individual blanks, feed rollers adjacent to said block, and means for rotating said rollers 80 at a speed greater than that of said push rod.

In testimony whereof I affix my signature in presence of two witnesses.

ROBERT KUCERA.
